UNITED STATES PATENT OFFICE.

EARLY T. GRIMES, OF ENTERPRISE, ALABAMA.

PLOW-SCRAPER-SETTING TOOL.

Specification of Letters Patent. Patented Sept. 29, 1914.

1,111,896.

Application filed April 29, 1914. Serial No. 835,305.

To all whom it may concern:

Be it known that I, EARLY T. GRIMES, a citizen of the United States, residing at Enterprise, in the county of Coffee, State of Alabama, have invented certain new and useful Improvements in Plow-Scraper-Setting Tools; and I do hereby declare the following to be a full, clear, and exact description of the invention, such as will enable others skilled in the art to which it appertains to make and use the same.

This invention relates to improvements in plow iron straightening devices and particularly to devices for setting plow scrapers to the proper angle.

The principal object of the invention is to provide a simple and novel device with which a plow scraper can be quickly and accurately set.

Other objects and advantages will be apparent from the following description, when taken in connection with the accompanying drawings.

In the drawings: Figure 1 is a plan view 25 of the device. Fig. 2 is a rear elevation showing the plow scraper in position. Fig. 3 is a vertical section on the line 3—3 of Fig. 2.

Referring particularly to the accompanying drawings, 10 represents a triangular base which is provided with openings to receive screws or other suitable fastening devices 11 for securing the base to a stationary block or other suitable solid support. 30 Formed integrally with the base and on two sides are the vertically extending rails or side members 12. The forward convergent ends of the rails 12 are cut away to provide a space in which is formed a staple or loop 13, said loop being also formed or cast integrally with the base and side rail. Between the forward ends, and just in rear of the space in which the staple is disposed is a block 14 which has its upper face inclined 35 downwardly in the direction of the staple. Formed in the block near the lower end is

a vertical recess 15. Loosely connected with the staple or loop is a lever 16, carrying a pin 17, adapted for passage in the recess 15.

In the operation of the device, the scraper eye or central portion 18 is heated and then the wings 19 are grasped in the hands and pulled toward each other so as to bend the scraper slightly. The scraper is then placed on the base so that the lower edges of the wings rest on the base. The lever 16 is then drawn down on the eye portion of the scraper until the pin 17 passes through the eye of the scraper and into the recess 15. The lever is then held down against the eye 60 portion of the scraper to firmly clamp the same against the block 14 while the scraper is struck with a hammer on each side of the lever until the wings are crowded over against the side rails. The scraper is then 65 properly set.

From the foregoing it will be seen that the device is simple in construction, and that the setting of a plow scraper is accomplished with ease and facility.

What is claimed is:

A plow setting device comprising a base having vertically extending and converging rails formed on two of its sides, the said sides being cut away at their convergent ends, a block mounted on the base in rear of the cut away portion, said block being formed with an inclined upper face, and a clamping lever pivotally connected to the base between the cut away portions of the side rails said lever having a vertically extending pin for engagement through the eye of a plow scraper and being arranged to hold the eye portion of the scraper on the block while the scraper is being set.

In testimony whereof, I affix my signature, in the presence of two witnesses.

EARLY T. GRIMES.
